UNITED STATES PATENT OFFICE

HERMANN PETSCH, OF RECKLINGHAUSEN, GERMANY, ASSIGNOR TO THE FIRM CARL STILL, OF RECKLINGHAUSEN, GERMANY

OPERATING DEVICE FOR COKE-OVEN DOORS

Application filed October 12, 1927, Serial No. 225,746, and in Germany October 13, 1926.

My invention consists in a device for removing and replacing the doors of horizontal coke oven chambers which device is provided with a rigid guide and so constructed that the door is removed, the coke pushed through the guide and the door replaced, while the device remains constantly in exactly the same position before the particular oven.

10 In the accompanying drawings, which represent diagrammatically an embodiment of the invention, Fig. 1 is a front elevation of the device seen in the direction towards the oven, Fig. 2 is a side elevation as a vertical 15 middle cross-section on the line 2—2 of Fig. 1, Fig. 3 is a plan view taken on the section line 3—3 of Fig. 2.

The apparatus consists mainly of a traveller *a* movable longitudinally in front of the oven battery; the traveller is supported below by rollers *b* running on a rail *d* fixed to the platform *c*, and above by rollers *e* running on a rail *f* laid on the top of the oven battery. A rigid guide *h* for use when the coke 25 is being discharged and consisting of a pair of vertical grate-like structures is arranged on the traveller *a*. Above this guide *h* is a crane jib *k*. The jib is supported by a pivot pin *i* at the end adjacent the ovens, and at 30 the outer end is supported and guided by rollers *n* running on a horizontal circular arc *m*. A trolley *r* with a supporting girder *s* extending downwards travels on the jib *k*; the coke oven door *t*, which is here shown as 35 a so-called plug door, can be suspended on the support *s* by holding attachments *u*, *v*. The motors and gearings required for the working are omitted from the drawings.

In operation, the device is moved in front 40 of the oven *x*, so that the guide *h* lies, in the plan view, directly in the horizontal axis of the oven and the jib *k* is positioned into the same oven axis as indicated in Fig. 3 by full lines; in this position it is, therefore, in line 45 with the guide *h*. The trolley *r* is moved with the supporting girder *s* along the jib *k* towards the oven until it is close before the door *t* to be removed. The latter is secured to the devices *u* and *v* and is freely suspended 50 and can now be moved by the trolley *r* rear-

wards through the guide *h* until it reaches the position outside the guide *h* indicated in Fig. 2. The jib *k* is now swung horizontally to one side, rotating about the pivot pin *i*, and is guided along the arc *m* by means of the rollers *n* until it has reached the position shown in dotted lines in Fig. 3. In this position the door *t* has been removed out of the way of the discharging coke and the guide *h*. The oven *x* can now, therefore, be emptied 55 and the coke pushed through the guide *h* on a ramp, for example an inclined ramp *z*, as shown in Fig. 2, or on to a loading device. When this has been effected, the jib *k* is swung back into its foregoing central position, the trolley *r* with the suspended door *t* is moved back through the guide *h* and the door is again replaced in the oven *x*. The apparatus, which during the whole working process described maintains unaltered its position in front of the oven *x*, is now ready for serving any other oven of the battery.

The apparatus can be used in connection with stationary horizontal or inclined coke ramps or with mechanical loading devices of 75 any construction.

What I claim is:—

1. A device for removing and replacing the doors of horizontal coke oven chambers, comprising a traveller movable in front of the ovens, a guide attached to said traveller for guiding the coke to be discharged, a jib mounted on said traveller above said guide, a vertical pivot pin on said traveller about which said jib can turn horizontally and a horizontal circular arc on said traveller guiding and supporting the outer end of said jib, a trolley travelling on said jib and means for supporting the door from said trolley.

2. A device for removing and replacing the doors of horizontal coke oven chambers, comprising a traveller movable in front of the ovens, a guide attached to said traveller for guiding the coke to be discharged, a jib mounted on said traveller above said guide, a vertical pivot pin on said traveller about which said jib can turn horizontally and a horizontal arc shaped track on said traveller guiding and supporting the outer end of said jib, a trolley travelling on said jib, a girder 100

suspended from said trolley and means for attaching the door to said girder.

3. A device for removing and replacing the doors of horizontal coke oven chambers, comprising a traveller movable in front of and in close proximity to the ovens, a guide attached to said traveller for guiding the coke to be discharged, and means carried by the traveller for supporting the door for movement bodily towards and away from the ovens in a horizontal plane through the said guide, said means permitting lateral movement of the door to either side of the guide after having passed the guide.

15 4. A device for removing and replacing the doors of horizontal coke oven chambers, comprising a traveller movable in front of the ovens, a guide attached to said traveller for guiding the coke to be discharged, a jib pivotally mounted on said traveller above said guide, an arcuate track support for the jib, a trolley travelling on said jib towards and away from said ovens, and means for supporting the door from said trolley.

25 5. A device for removing and replacing the doors of horizontal coke oven chambers, comprising a traveller movable in front of the ovens, a platform below said traveller, a rail on said platform, a rail on the top of the oven battery, rollers secured to said traveller running on said rails, a guide attached to said traveller for guiding the coke to be discharged and means carried by the traveller for supporting the door for movement towards and away from the ovens through the said guide, said means permitting lateral movement of the door to either side of said guide.

40 6. In combination, a bank of horizontal coke ovens and a platform in front of and in close proximity to the discharge ends thereof, a traveller supported by said ovens and platform and arranged to move across the discharge end of said ovens, spaced coke guiding elements carried by the traveller and adapted to be arranged on either side of the axis of an oven chamber, means carried by said traveller for supporting an oven door for movement bodily toward and away from 45 an oven chamber through said guides in line with the axis of the oven and in a horizontal plane, said means being oscillatable in either direction to permit lateral movement of the door to either side of the oven axis 50 after having passed the guiding elements.

65 7. In combination in a bank of horizontal coke ovens and a platform extending across the front of the same, a traveller supported upon said ovens and platform and arranged to move across the discharge end of the same, a pair of spaced guide elements carried by said traveller, a vertical pivot pin arranged intermediate the guide elements above the same, an arcuate track carried by 65 the traveller, a jib pivoted on said pin and

having its free end supported by said track, a trolley movable over said jib, and means carried by the trolley for supporting an oven door for movement between said guide elements and in line with the axis of an oven chamber, said jib arranged to swing on said pivot over the track to permit shifting of the door to either side of the axis of the oven chamber.

70 In testimony whereof I affix my signature.

75 HERMANN PETSCH.
